UNITED STATES PATENT OFFICE.

ELTON N. JOHNSON, OF LA SALLE, NEW YORK.

IRONING BOARD.

Application filed April 25, 1928. Serial No. 272,786.

This invention relates to that class of ironing boards which are adapted to be folded up into a closet or cabinet, so as to be out of the way when not in use, and the invention 5 has for its object to provide a suitable mounting for an ironing board, of this class, which is specially adapted for small apartments where the space is limited. To this end the invention comprising simple means 10 whereby the ironing board may be let down from the closet or cabinet, and when thus let down may be swung aside to any desired lateral position to suit the convenience of the user. The invention also provides means 15 whereby the ironing board may be adjusted to different heights when in working position, to accommodate persons of different heights.

In the accompanying drawings Fig. 1 is 20 an elevation showing the ironing board in raised position in the cabinet with the door of the cabinet open. Fig. 2 is a sectional view on line 2—2, Fig. 1. Fig. 3 is a sectional view similar to Fig. 2 with the ironing 25 board let down and swung aside to working position. Fig. 4 is a sectional side view showing the ironing board lowered to working position as in Fig. 3. Fig. 5 is a sectional view showing the ironing board in 30 folded position within the cabinet as in Fig. 1. Fig. 6 is a broken out detail view of the ironing-board supporting-rod or bar and co-operating parts, and Fig. 7 is a partial view of the same. Figs. 8 and 9 are detail side 35 and bottom views, respectively, of the spring bar by which the supporting-bar 14 may be sustained in different positions of vertical adjustment. Fig. 10 is a detail view showing the spring catch which holds the ironing 40 board upright within the cabinet. Fig. 11 is a detail view showing the hinge mounting of the ironing board legs.

Referring to the drawings, 12 denotes the 45 closet or cabinet which may be of any suitable construction and which will preferably be provided with a door 13. Within the closet or cabinet, near one side thereof, is pivotally mounted a vertical rod or bar 14 having near its bottom a laterally extending 50 arm 15 encircled by eyes or loops 16 extending from a cross bar or cleat 17 to which the ironing board 18 is attached, this construction thus providing a hinged connection 55 between said ironing board and the said laterally extending arm 15 so that the ironing board may be raised or lowered as may be desired. It will be noted that said arm 15 extends from said rod or bar 14 in a direction parallel to the width of said board 18. The eyes or loops 16 are positioned on the 60 laterally extending arm 15 by means of stop collars 19 attached to said arm. The rod or bar 14 is pivotally secured in place by loops 14^a attached to the cabinet 12 and by which loops said rod or bar is encircled so that it 65 may turn within said loops 14^a when the arm 15 is swung out or in.

The length of the arm 15 is approximately 70 equal to the width of the ironing board 18 and the loops 16, by which said ironing board is pivoted or hinged to said arm, are widely separated from each other, (see Figs. 1 and 3), thus affording stability to said board so that sidewise tilting thereof, when 75 in use, will be prevented.

Also hinged to the laterally extending arm 15, by loops 16^a are connected legs 20 to which is pivotally attached a brace 21 comprising strengthening crossing strips 22, and cross-rods 21^a and 22^a, the free end of said 80 brace 21 being adapted to engage any one of a series of stops 23 to hold the ironing board in working position, as more clearly shown in Fig. 4. The legs 20 are connected together, near their free ends, by a cross rod 85 20^a. Attached to the bottom of the ironing board is a spring catch 24 which is adapted to engage the cross-rod 21^a forming part of the brace 21, so that the said brace and the legs connected therewith may be held in position 90 against the ironing board when the latter is to be folded up within the cabinet.

The vertical rod or bar 14 is provided 95 with three annular grooves 14^b, and attached to the inside of the cabinet, by a flange 25^a, is a spring bar 25, provided at its lower end with a flange 25^d having a semi-circular notch or recess 25^b adapted to enter any one of said grooves and thus support 100 the said rod or bar in different vertical positions, depending upon which one of said grooves is engaged by said flange. By reason of this construction the said rod or bar 14 and the ironing board connected therewith, as above described, may be adjusted 105 to different heights to accommodate different persons. Also the said annular grooves permit the said rod or bar to turn, in the different positions of vertical adjustment of the ironing board, in swinging the 110 said board to different horizontal positions. Thus if the upper one of said grooves 14^b

is engaged by said flange 25^d, as shown in Figs. 1, 4 and 6, the ironing board will be in its lowest position; and for a medium adjustment the said rod or bar may be lifted 5 to enable the said flange 25^d to engage the middle one of the said grooves; or for the highest adjustment of the ironing board the said rod or bar may be lifted still further to enable said flange to enter the lowermost 10 of said grooves, to accommodate a tall user.

The semi-circular notch or recess 25^b and the annular grooves 14^b in the rod permit the rod 14 to turn when the arm 15 is to be swung out or in, as above indicated. The 15 spring bar 25 is provided with a nib 25^c for convenience in springing it out of any one of the grooves 14^b with which it may be engaged, when it is desired to raise or lower the said bar.

20 The several stops 23 on the ironing board 18 serve to hold the legs 20 and the brace 21 in the several positions of adjustment of the ironing board above referred to. The flange 25^d rests, in the different positions 25 of vertical adjustment of the rod or bar 14 above described, on the uppermost of the eyes or loops 14^a in which the bar 14 is pivotally mounted, as more clearly shown in detail view Fig. 6.

30 From the foregoing it will be understood that the invention provides a convenient construction whereby an ironing board may be mounted within a cabinet in such a manner that it may be swung down to horizontal 35 position, and may then be swung laterally to any desired angle, as indicated by full and dotted lines in Fig. 3; and it will also be understood that the invention comprises simple means by which the ironing 40 board may be adjusted to different vertical working positions, to accommodate persons of different heights.

Any suitable catch or latch may be provided to hold the ironing board in an up- 45 right position when folded up in the closet or cabinet 12. This is effected, in the construction shown, by a spring catch 26 mounted on a bar 27 attached to the upper end of the rod or bar 14, said bar 27 having 50 a stop flange 26^a for the said spring catch and a stop flange 28^a for the ironing board. The clearances shown in Fig. 10 between the shoulder 26^a on the spring catch 26 and the stop flange 28^a are provided to accommodate 55 the usual ironing board covering.

Having thus described by invention I claim and desire to secure by Letters Patent:

1. The combination with a cabinet, of a vertical rod pivotally mounted therein 60 nearer one side than the other thereof and provided with a laterally extending arm, an ironing board having pivotal connections with said arm, at two widely separated points, so that said board may be raised, to

enable it to be folded into said cabinet, or 65 may be lowered into working position, and means for sustaining said ironing board when lowered to working position, said arm extending from said rod in a direction parallel to the width of said board and being 70 of a length approximately equal to the width of said ironing board to afford room for proper spacing apart of said pivotal connections.

2. The combination with a suitable cab- 75 inet, of a vertical rod pivotally mounted therein and provided with a laterally ex- 80 tendsing arm, an ironing board having a pivotal connection with said arm so that it may be raised to enable it to be folded into 85 said cabinet or may be lowered into working position, means for sustaining said ironing board when lowered to working position, and means for holding said rod and the ironing board connected therewith in differ- 90 ent vertical working positions, to accommo- 95 date persons of different heights.

3. The combination with a suitable cab- 100 inet, of a vertical rod pivotally mounted therein and provided with a laterally ex- 105 tendsing arm, an ironing board having a pivotal connection with said arm so that it may be raised to enable it to be folded into said cabinet or may be lowered into working po- 110 sition, means for sustaining said ironing 115 board when lowered to working position, said rod being provided with a plurality of annular grooves, and a spring bar having a notched flange adapted to be engaged with any one of said grooves to support said rod and the ironing board connected therewith, to accommodate persons of different heights.

4. The combination with a suitable cab- 120 inet, of a vertical rod pivotally mounted therein and provided with a laterally ex- 125 tendsing arm, an ironing board having a pivotal connection with said arm so that it may be raised to enable it to be folded into said cabinet or may be lowered into working position, means for sustaining said ironing board when lowered into working position, said rod being provided with a plurality of annular grooves, and a spring bar having a notched flange adapted to be engaged with any one of said grooves to support said rod and the ironing board connected therewith, in different vertical positions, to accommodate persons of different heights, said sus- 130 taining means comprising legs having a hinged connection with said ironing board, and a brace having a hinged connection with said legs, said ironing board having a plurality of stops to be engaged by said brace in the different positions of vertical adjustment of said ironing board.

In testimony whereof I affix my signature.

ELTON N. JOHNSON.
